CLAIM

The ornamental design for a linear wall or ceiling mounted luminaire with rotatable optics, as shown and described.

DESCRIPTION

FIG. 1 is a perspective view of one embodiment of the luminaire showing the design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is a perspective view of an alternative embodiment of the luminaire of the present invention;

FIG. 9 is a top view thereof;

FIG. 10 is a bottom view thereof;

FIG. 11 is a front view thereof; and,

FIG. 12 is a rear view thereof.

With the exception of the length, it is understood that the views of the second embodiment are similar to the first embodiment.

The broken lines shown on FIGS. 2 and 3 depict environmental structure and form no part of the claimed design.
